UNITED STATES PATENT OFFICE.

SWITS CONDÉ, OF OSWEGO, NEW YORK.

DESIGN FOR A KNITTED GARMENT.

SPECIFICATION forming part of Design No. 19,063, dated April 30, 1889.

Application filed March 18, 1889. Serial No. 303,780. Term of patent 7 years.

To all whom it may concern:

Be it known that I, SWITS CONDÉ, a citizen of the United States, residing at Oswego, in the county of Oswego and State of New York, have invented and produced a new and original Design for a Knitted Garment, of which the following is a specification, reference being had to the accompanying drawing, forming part thereof.

10 The drawing shows a front elevation of a blouse containing my design, one view being deemed sufficient to fully illustrate my design.

15 The leading feature of my design consists in a garment composed of vertical stripes provided at the front with lacing-cord *c* and at the bottom with a contracted band, *b*.

20 A *A* represent the vertical stripes composing the garment, to the bottom of which is secured the contracted band *b*, which is composed of horizontal stripes. This band causes

the upper part of the garment above the contracted band to overhang the said band and to be gathered or ruffled, and produces a garment having its lower extremity of less width 25 than the upper portion, presenting a pleasing appearance.

What I claim is—

The design for knitted garments herein shown and described, the same consisting of 30 vertical stripes composing the upper part of the garment and a contracted band at the lower part, substantially as set forth.

In testimony whereof I have hereunto signed my name, in the presence of two attesting witnesses, at Oswego, in the county of Oswego, in the State of New York, this 12th day of March, 1889.

SWITS CONDÉ.
